UNITED STATES PATENT OFFICE.

GEORGE FERGUSON, OF APELDOORN, NETHERLANDS, ASSIGNOR TO APELDOORNSCHE MACHINEFABRIEK EN METAALGIETERIJ VOORHEEN LOOG LANDAAL, OF APELDOORN, NETHERLANDS, A LIMITED LIABILITY COMPANY UNDER THE LAWS OF THE KINGDOM OF THE NETHERLANDS.

COMPRESSION REFRIGERATING MACHINE.

1,410,394.

Specification of Letters Patent. Patented Mar. 21, 1922.

Application filed November 8, 1918. Serial No. 261,643.

To all whom it may concern:

Be it known that I, GEORGE FERGUSON, a subject of the Queen of the Netherlands, residing at Apeldoorn, Province of Gelderland, in the Kingdom of the Netherlands, have invented certain new and useful Improvements in Compression Refrigerating Machines, of which the following is a specification.

10 The invention relates to a compressing cylinder device for refrigerating machines, working with two evaporating pressures.

With ordinary compressors, gas of a certain pressure is admitted into the cylinder 15 during the suction stroke; with refrigerating machines, working with two evaporating pressures, two functions must be performed during the suction stroke, namely first the low pressure gas and afterwards the high 20 pressure gas must be brought into the cylinder. For these two functions together only about the same course of time is available as is the case for the inlet of the gas into a compressing cylinder, working with one single 25 evaporating pressure. It will therefore be necessary to perform the inlet of gases of two different evaporating pressures in such a manner, that the gas of one pressure does not influence the admission of the other gas. 30 in an unfavourable way; the current which may be favourable for one gas may exert a disadvantageous influence upon the inlet of the other gas.

The present invention relates to a compressing cylinder for refrigerating machines, working with two evaporating pressures, with which cylinder a favourable inlet for both gases is obtained.

With the special construction of the compressing cylinder, mentioned above, the 40 temperature of the cylinder is influenced in a favourable way, as this special construction can be compared with the water jacket of a compressor, working with superheating.

45 With the present invention the working part of the cylinder is enclosed entirely or nearly entirely by a jacket, which by a ring of small apertures gives access for the high pressure vapours into the cylinder. These 50 apertures are opened during the last part of the suction stroke by the piston, and are so formed, that their section becomes gradually narrower in the direction from the

jacket into the cylinder. In the same way the jacket is connected to the high pressure 55 pipe by an opening which grows wider in the direction of the jacket.

On compressing cylinders similar apertures for the inlet, of which the section increases progressively, are not novel; the 60 novel feature however is the application of such apertures to a compressing cylinder, working with two evaporating pressures, thus obtaining a favourable inlet into the cylinder of both the low pressure and the 65 high pressure vapours.

With ordinary compressing cylinders, the suction into the cylinder begins at the beginning of the suction stroke, and is continued even during the first part of the compression stroke. The slow closing of the suction valve has the consequence, that during the low speeds of the piston near the dead center, gas can enter into the cylinder. 70

When the end of the piston stroke, as is 75 the case with the present arrangement, is used for the admission of the high pressure gas, this not only decreases the efficiency of the suction stroke to fill the cylinder with low pressure gas, but especially eliminates that part of the stroke during which the high pressure gas is admitted; on account of the low piston speed, the cylinder is filled with gas, which under ordinary arrangements would not enter the cylinder on account of the great velocity of the piston. 80

In order to insure the cylinders being filled as much as possible with low pressure gas, the cylinder is provided with a large 90 number of circumferential apertures through which the high pressure gas enters. By this means, nearly the whole suction stroke is first used to fill the whole cylinder with low pressure vapours, which, vapors can enter into the cylinder, when the piston moves at 95 low speed also.

The small size of the apertures for the admission of the high pressure vapours, giving a long period of admission for the low pressure gas, results of course in a much 100 shorter period of admission of the high pressure vapours. The admission of these high pressure vapours, entering as they do into the cylinder as soon as the piston opens the apertures (the suction valve through which 105 the low pressure vapours enter, being closed

by the rise of the pressure in the cylinder) must also be performed as completely as possible and must be effected so that at the end of the period of admission, the pressure in the cylinder is nearly equal to the pressure in the high pressure evaporator.

This is obtained in the present invention by arranging the receiver quite near to the apertures of admission which are arranged 10 around the cylinder and by the special form of these apertures between receiver and cylinder and of the inlet opening of the receiver. By extending the receiver over the entire working part of the cylinder, this receiver also acts as a cooling jacket.

The invention is illustrated and explained by the accompanying drawing, in which:

Fig. 1 represents a complete refrigerating plant according to the present invention, 20 working with two evaporating pressures in a single compressing cylinder which in the present case is a single acting vertical machine and in which the suction valve is arranged in the piston.

Fig. 2 is on a larger scale a vertical section through the apertures for the inlet of the high pressure vapours into the cylinder and

Fig. 3 is a front view of these apertures. 30 1 is a regulating cock, as it is generally used with compression refrigerating machines. Through this cock the circulating liquid streams from a condenser, which is not shown in the drawing, to the high pressure evaporating coil 2. In this high pressure evaporator heat is absorbed at high temperature, thus evaporating a part of the liquid therein, so that after passing the high pressure evaporator there is a mixture of 35 gas and liquid. This mixture is led to the liquid separator 3, which eventually forms part of the high pressure evaporator. From this separator the high pressure gas is sucked off by the compressor through a pipe 4 in a way, which will afterwards be explained. The liquid collects at the bottom of the separator and is discharged through a float-device 5 to the low pressure evaporator 7.

The liquid which is discharged into the 50 low pressure evaporator 7, is evaporated therein at a low pressure so that in this low pressure evaporator heat is absorbed at a low temperature. From there the developed vapours are led in the usual way through a 55 pipe 8 to the suction opening 9 of the compressor which is adapted to communicate with the working part of the compression cylinder as hereinafter described.

The drawing gives a vertical single acting 60 compressing cylinder 11, into which the vapours developed in the evaporators are sucked by a hollow piston 10, which is provided at one side with a lateral opening or port 10' and at the top is provided with a suction 65 valve 12. The high pressure vapours enter

into the cylinder as soon as the piston 10 opens the apertures 13 at the end of the downward stroke. The cylinder then already is filled for the greater part with low pressure vapours which in the usual way are 70 sucked into the cylinder from the low pressure evaporator 7, in which by the evaporating of the liquid at a low pressure and at a low temperature, cold is produced.

The admission of the low pressure vapours is continued from suction chamber 9 through hollow piston 10 and pressure controlled valve 12, until the rise of the pressure in the cylinder (on account of the admission of the high pressure vapours through 75 the apertures 13) closes the suction valve 12. These apertures 13, which in axial direction of the cylinder are of small size, are arranged in a large number around the entire circumference of the cylinder. It will be 80 preferable to give them a shape as depicted in Figures 2 and 3 so that these apertures have a circular shape 14 at the inner side of the cylinder and at the outer side of the cylinder increase in axial direction to an oblong shape 15. With this shape of the apertures, the material of the cylinder practically 85 is not weakened and the casting of the cylinder is influenced in a favourable way by this form of the apertures. The cores of the 90 holes are much stronger and can be attached in a solid way and therefore more accurately to the core of the jacket, than would be possible with small cores of constant circular 95 section.

More important however is the form of these apertures for the admission of the high pressure vapours into a cylinder. In the receiver 16, which is provided with these 100 apertures 13 and which encloses the cylinder all around, the high pressure vapours enter from the evaporator through pipe 4 and opening 17, which enlarges in a conical form in the direction of the receiver. This receiver enables the gas to flow uniformly 105 through all the apertures 13 in the cylinder. In the receiver, the velocity of the gas is naturally much less than in the apertures 13 and the pipe 4; therefore between pipe 4 and the cylinder the current of gas is first retarded and then accelerated.

Each transformation of velocity into pressure and of pressure into velocity is accompanied by losses caused by friction, which result in the production of useless 110 or disadvantageous heat, instead of useful energy. This is of great importance, especially when, as in the present case, high velocities must be obtained during a short period of admission. These losses are the 115 greatest, when these transformations are performed with interruptions. With the form of the apertures 13 and the opening 17, growing gradually larger in the direction of the receiver, this transformation of energy 120

is performed more gradually, thus decreasing the losses caused by friction and therefore obtaining a more perfect and rapid inlet of the high pressure gases into the cylinder.

5 With the up-stroke of the piston, first the apertures 13 are shut off, the low pressure and high pressure vapours together are compressed and then discharged through a valve 10 in the cylinder cover (not shown).

10 The jacket or receiver 16 of the cylinder extends nearly over the whole working part of the cylinder. The high pressure vapours therefore act as a cooling medium on this 15 part of the cylinder, which is heated by the heat of compression; thus this receiver serves the same purpose as a water jacket.

20 The same jacket and apertures of admission, as described here above, can also be applied to single acting compressing cylinders, in which the suction-valve is placed in the cylinder-cover, or to double-acting cylinders, in which one or more suction-valves are arranged at each end of the cylinder.

25 What I claim is:

1. In a gas compressor for refrigerating systems working with two intake pressures, in combination, a cylinder, a hollow piston fitting within said cylinder having a lateral 30 opening and an opening controlled by a pressure actuated valve, a jacket substantially enclosing the working part of said cylinder and forming a receiver for high pressure gas, a plurality of apertures formed in 35 said cylinder adapted to be uncovered by said piston when approaching the end of the

suction stroke for admitting high pressure gas into the cylinder, a low pressure gas receiving chamber in communication with said cylinder through said lateral and valve controlled openings, whereby low pressure gas is admitted to said cylinder during the suction stroke of the piston until said apertures are uncovered and high pressure gas is admitted in quantities sufficient to exert pressure on said valve and close the same, the high pressure gas in said jacket acting as a cooling medium for the working part of the cylinder.

2. In a gas compressor for refrigerating systems working with two intake pressures, in combination, a cylinder, a piston fitting within said cylinder, a jacket substantially enclosing the working part of said cylinder and forming a receiver for high pressure gas, a plurality of apertures formed in said cylinder for the admission of the high pressure gas into the cylinder, said apertures being so formed that their section grows gradually wider in the direction of the jacket and being opened during the last part of each suction stroke of the piston, and a pipe connecting said jacket with a high pressure chamber through an opening in said jacket the section of which becomes gradually wider in the direction of the jacket.

In testimony whereof I have hereunto set my hand.

GEORGE FERGUSON.
